UNITED STATES PATENT OFFICE.

HUGH MACLEAN, OF PORTLAND, OREGON.

MEANS FOR FASTENING CARPET TO CONCRETE FLOORS.

1,070,273.

Specification of Letters Patent. Patented Aug. 12, 1913.

Application filed March 23, 1912. Serial No. 685,787.

To all whom it may concern:

Be it known that I, HUGH MACLEAN, a citizen of the United States, and a resident of the city of Portland, county of Multnomah, and State of Oregon, have invented a new and useful Improvement in Means for Fastening Carpet to Concrete Floors, of which the following is a specification.

My invention has for its object the providing of inexpensive and effective means by which carpets may be securely fastened at their edges on concrete floors at an economic cost.

I carry out my invention by providing wooden strips secured in position by metallic tie strips, the latter being anchored in the wall. And I conceal the edge of the carpet by means of a shoe molding, so as to present a harmonious aspect to the eye.

20 My invention embodies further the particular features hereinafter fully described.

In the accompanying drawings constituting a part of this specification: Figure 1 is a sectional elevation, in perspective, of a portion of a partition wall and its floor base, showing my invention as applied to such construction; in this view the carpet and filler are omitted; Fig. 2 is a sectional elevation, in perspective, of an exterior wall and its floor connections, showing my invention as applied to the edges of a room abutting on such exterior wall; Fig. 3 is a diagrammatic sectional elevation, showing a different method of anchoring the metallic tie strip in wall or floor; Fig. 4 is another mode for accomplishing the same result; Fig. 5 is a sectional elevation, in perspective, of a wooden carpet nailing strip, showing the recess which may be used in order 40 to bring the top of the metallic tie strip flush with the top of carpet nailing strip; and Fig. 6 is a diagrammatic sectional elevation illustrating the use of a wooden carpet nailing strip having a flat level top.

45 a and o represent a partition wall and an exterior wall respectively, the walls comprising the usual plaster grounds b, plaster face c, wire ducts d, and mortar joints e.

f is a wood base, g a wooden shoe, h represents fragments of carpet, and i the carpet filler.

On the finished surface, m, of the concrete floor, n, is placed a carpet nailing strip, j, running entirely around the edges of the 55 room. This strip is secured in place by metallic tie strips, k, which are anchored

in the floor or wall and bent back over and conformed to the upper surface of said nailing strip, to which said turned back portions are nailed. r is a molding topping the 60 wood base. Recesses p may be cut in the carpet nailing strip, if desired, so that the top of the metallic tie strip will be flush with the surface of said carpet nailing strip. The top of the carpet nailing strip may 65 also be made with a level surface, as shown at s (see Fig. 6) and the tie strip j' conformed thereto, so that the tension of the carpet will be horizontal, which is more 70 advantageous than a construction whereby the pull is not at right angles to the restraining means.

For edges abutting partitions the construction is as follows: While the mortar in the mortar joint is still green, the flat metallic tie strips are inserted under the plaster grounds. After the wood base is in place a carpet nailing strip (j, for example) is laid against the base of the wall, as shown, and the metallic tie strip, k, is bent back 80 over and nailed to the former, as shown in Fig. 1. The carpet (h) is laid over the carpet filler (i) and is nailed to the carpet nailing strip, as illustrated in Fig. 2. The shoe molding, g, is then placed in position, 85 and the beveled base of same serves to hold the carpet in place and also to conceal edges of same.

For edges abutting, or exterior walls, the metallic tie strips, k, are laid on the rough 90 concrete floor, n, and embedded in the concrete finish m. The metal strips being formed and arranged in either of the modes shown in Figs. 2, 3, or 4, for the purpose of anchoring same. In other respects the procedure is just the same as above. The described methods may also be used at the base of columns. A plurality of tie strips are used for securing the nailing strip in place, and they are placed convenient distances apart.

I claim:

1. The combination with a wall and concrete floor, in a building, of a tie strip anchored at the base of the wall, a nailing strip 105 laid against the base of such wall on the floor, the tie strip superimposed upon the nailing strip, and a molding affixed to the wall and resting upon said nailing strip.

2. The combination with a wall and concrete floor, in a building, of a tie strip anchored at the base of the wall, a nailing strip 110

laid against the base of such wall on the floor, the tie strip superimposed upon the nailing strip, and means holding down that side of the nailing strip abutting against the wall.

3. The combination with a wall and concrete floor, in a building, of a plurality of metallic tie strips anchored at the base of the wall, a nailing strip laid against the base of such wall on the floor, the free ends of the tie strips being bent back over the nailing strip, and a molding affixed to the wall and resting upon said nailing strip.

4. The combination with a wall and concrete floor, in a building, of a plurality of metallic tie strips anchored at the base of the wall, a nailing strip laid against the base of such wall on the floor, the free ends of the tie strips being bent back over the nailing strip, and means holding down that side of the latter abutting against the wall.

HUGH MACLEAN.
